TYPEWRITER

Harry Bates, New York, N. Y., assignor to Bates Laboratories, Inc., New York, N. Y., a corporation of New York

Application February 24, 1934, Serial No. 712,725

10 Claims. (Cl. 197—22)

This invention relates to typewriters in general.

Among the objects of the present invention, it is aimed to provide a typewriter having a type selector which will cooperate with a plurality of type bars to select the same according to the message to be transcribed, recorded or the like and the actuation of which selector after selection will cause printing of the type bar selected.

10 It is still another object of the present invention to provide an improved typewriter construction especially adapted for use as an educational machine to instruct the uninitiated or child in the use of a universal keyboard including a universal keyboard, a selector to be guided by said keyboard, and a plurality of type bars selected according to the positioning of said selector with respect to said keyboard and actuated into printing position by a second actuation of said selector.

15 It is still another object of the present invention to provide a typewriter having a plurality of type bars positioned in a row, a universal keyboard, and a selector operatively associated with said keyboard and type bars to select the type bar corresponding to the character designating area formed on said keyboard and in turn to actuate said type bar into printing position after having been properly selected.

20 It is still another object of the present invention and one of the main objects of the same to provide a typewriter particularly adapted for use as an educational machine to instruct the child or uninitiated into the use of the right hand side and the left hand side of a universal keyboard by the right hand and left hand respectively and exclusively of the operator.

25 These and other features, capabilities and advantages of the invention will appear from the subjoined detail description of specific embodiments thereof illustrated in the accompanying drawings in which

30 Figure 1 is a plan view partly broken away of one embodiment of the present invention;

35 Fig. 2 is a section on the line 2—2 of Fig. 1;

40 Fig. 3 is a fragmental section on the line 3—3 of Fig. 2;

45 Fig. 4 is a fragmental detail of one of the type bars in printing position of the embodiment illustrated in Fig. 1;

50 Fig. 5 is a section on the line 5—5 of Fig. 2;

55 Fig. 6 is a section on the line 6—6 of Fig. 2;

60 Fig. 6A is a perspective of the guide for a type bar while printing;

Fig. 7 is a fragmental section of a second embodiment of the present invention; and

Fig. 8 is a section on the line 8—8 of Fig. 7.

In the embodiment illustrated in Figs. 1 to 6A inclusive, there is provided a frame 1 having the supporting plugs 3 connected thereto. The frame 1 as indicated consists essentially of the front wall 4 and a rear wall 5 which are connected to one another by the side walls 6 and 7. From the side wall 6 to the side wall 7, there extends the universal keyboard 8 which in the present embodiment is fixed and has formed thereon a plurality of depressions 9 corresponding in position relative to one another to the keys of a universal keyboard. In addition to the depressions 9 corresponding to the keys of a universal keyboard there are provided in the present instance four depressions 10 at the left hand end of the keyboard which may serve as space designating areas when no printing takes place. For 10 advancing the carriage a letter space in accordance with the universal keyboard in the usual way, there is provided the space bar 11. When the space bar 11 is provided, the blank depressions 10 may be omitted. On the other hand, the 15 universal keyboard may be supplemented with additional keys and the blank depressions 10 in such case serve as such additional keys of character designating areas for corresponding additional type bars.

20 In the present instance, and as forming an important part of the present invention, the depressions 9 to the right of the dash and dot line 12 can only be used for registration with the selector finger 13 and the depressions 9 and 10 to 25 the left of the line 12 can only be used for registration with the selector finger 14. The line 12 divides the keyboard 8 to correspond to the division extensively accepted by typewriter schools and the like although the keyboard 8 30 may be divided in any suitable other way for cooperation with two selector fingers according to the present invention without departing from the spirit of the same.

35 The selector fingers 13 and 14 are operatively connected with two separate sets of type bars 15 and 16 respectively for cooperating with the paper mounted in the usual way on the platen P. Each type bar 16 as an instance as shown in Fig. 4, has a plane upper face 17 and a type supporting head 18 at the upper end thereof having lower case type 19 and upper case type 20. The head 18 extends to one side of the type bar 16 in a generally upward direction as shown and has a spur 21 extending from the enlarged lower 40

portion of the type bar 16. Each type bar 16 has a round opening 22 in its lower enlarged portion to pivotally receive the hollow shaft 23 which has an angular longitudinally extending channel to receive the angular shaft 24 having the rounded ends 25 journaled in the side bars 6 and 7.

Of the type bars 16, there are in the present instance nineteen in number corresponding to the nineteen depressions 9 having characters marked thereon to the left of the line 12 of the keyboard 8. The type bars 16 are spaced from one another predetermined distances corresponding to the distances between the depressions 9 on an imaginary common projected line. As an instance, on a common projected line from the left to the right, the depressions 9 on the left side of the line 12 of the keyboard 8 will assume the following order:

20 q, a, 1, z, w, s, 2, x, e, d, 3, c, r, f, 4, v, t, g, b
for the lower case with the greatest space between the letters "g" and "b" on said projected line and will assume the following order:

25 Q, A, /, Z, W, S, —, X, E, D, \$, C, R, F, €, V, T, G, B
for the upper case type and be spaced from one another with the greatest space between the letters "G" and "B" on said projected line whereas 30 the type bars 16 reading from left to right will succeed one another in the reverse order and be spaced to correspond to the distances between the depressions 9 aforesaid.

35 Adjacent to the type bar 16 having the type "b" and "B", there will be fixed on the hollow shaft 23 the enlargement 26 of the arm 27 extending forwardly across the keyboard 8 to the front frame wall 4. On this bar 27, there is slidably mounted the finger piece 28 having secured thereto the flexible arm 29 on the rear end of which is formed the selector finger 14.

40 Adjacent to the type bar 16 having the type "q" and "Q", there is fixed on the shaft 23, the sleeve 30. From the plane face of the sleeve 30 to the plane face of the enlargement 26, there extends the yieldable spring strip 31 preferably slitted as shown to form the yieldable lips 32, each engaging the plane face 17 of a type bar 16.

45 The shaft 23 with the type bars 16 is slidably mounted on the shaft 24 and the type bars 16 are so positioned relative to the depressions 9 on the left hand side of the line 12 that the registration of the selector finger 14 with a depression 9 will position a corresponding type bar 16 in the printing position defined by the recessed portion 33 of the guide plate G, see Fig. 6A.

50 The bar or lever 27 with the shafts 23 and 24 will rock about the axis of the shaft 24 to cause the printing action to take place. For this purpose, there is provided the trip lever 34 which is fixed on the shaft 35 journaled at its left hand side in the side frame wall 6 and at its right hand side in the bracket 36.

55 The trip lever 34 has the trip finger 37 at its upper end to register with the spur 21 of the type bar 16 which is positioned in printing position. The shaft 35 also has fixed thereon the projection 38 which is operatively connected by the link 39 with the projection 40 also fixed on the shaft 70 24. Consequently when the finger 28 is depressed to effect a printing action, the link 39 and trip arm 34 will cooperate to cause the type bar 16 to swing into impression position against the resistance of the resilient lip 32 of the strip 31 in alignment with the type bar selected as illustrat-

ed in Fig. 4 without effecting the movement of the remaining type bars 16 on the shaft 23.

5 For returning the several parts to normal position, the spring 41 is provided connecting the shaft 35 with the end of the link 39 connected to the projection 40, see particularly Figs. 2 and 3. To serve as a limiting stop, the sleeve 28 cooperates with the side bar 7 to limit the movement of the lever 27 so that the selector finger 14 cannot register with any depressions 9 to the right of the depression 9 bearing the type "b" and "B". At most, if the selector finger 14 were caused to register with the depression 9 bearing the markings "5" and "%" due to the space between the type bar carrying the type "g" and "G" and the bar carrying the type "b" and "B", no impression would be made and the operator would immediately realize his mistake.

10 The actuation of the platen P for line spacing and letter spacing and the feed of the printing ribbon 42 may be effected in the usual way and will now be described.

15 The platen P has the usual finger manipulating knobs 42 at the ends thereof and has its diminished portions between the knobs 42 and the platen P journaled in the upper ends of the bracket arms 43 and 44 which extend up from a base 45 having inclined longitudinal edges to cooperate with the bayonet slideway formed at 46 and 47 in the casting 48 which has vertically 20 extending inclined edges to cooperate with the bayonet slideway formed at 49 and 50 in the rear wall member 5.

25 The casting 48 has a shoulder 51 normally resting on the shoulder 52 of the rear wall 5 and so maintained by the springs 53, connecting the casting 48 with the abutments 54, only one spring 53 and one abutment 54 being shown.

30 The casting 48 is pivotally connected by the links 55 with the rear ends of the shift levers 56 which are fixed to the shaft 57 journaled in the side walls 6 and 7. The front ends of the shift levers 56 terminate in the upright portions 58, each provided with a finger engaging key member 59 at its upper end, the upright portions 58 40 extending upwardly through the openings 60 formed in the keyboard 8 with the keys 59 located above the keyboard 8 as shown.

35 For shifting the platen to effect printing of the upper case type 20 of the type bars 16, it will only be necessary to depress either of the keys 59 thereby raising the casting 48 and with it the bracket arms 43 and 44 to position the platen. For convenience the stops 60 are provided to accurately determine the upper position of the platen P when it is desired to print upper case type 20.

45 The line spacing of the platen is effected in the usual way, there being provided the toothed wheel 61 fixed concentric with the platen P to be engaged by the friction creating spring 62. The letter space of the platen P is effected by the escapement now to be described.

50 To the lower side of the base 45, there is pivotally connected the toothed rack 63 which is yieldably maintained in engagement with the holding pawl 64 and the advancing pawl 65 by the flat spring 66 secured to the casting 48. The holding pawl 64 is pivotally mounted on a pin 68 mounted on the casting 48 and is connected by the spring 67 to maintain its toothed end in engagement with the teeth of the rack 63. The stop pin 68 carried by the casting 48 limits the movement of the pawl 64 to permit the rack 63

to be released by the finger piece 69 when returning the platen P for a new line.

The advancing pawl 65 is pivotally connected to the link 70 which is pivotally mounted on a pin extending upwardly from the face of the casting 48. The pawl 65 is provided with a stop 71 normally pressed into engagement with the edge of the link 70 by the spring 72.

The spring 73 on the other hand normally urges the link 70 away from the rack 63 into engagement with the abutment 174 at the upper end of the lever 174 fixed on the shaft 75 journaled in the side walls 6 and 7.

The shaft 75 has a rearwardly extending arm 76 fixed thereto and engaging the lower face of the spring 71 secured to the inner face of the rear wall 5 yieldably to maintain the abutment 174 in engagement with the joint formed by the link 70 and pawl 65, see Fig. 5. In order to letter space the platen P without printing, it is therefore only necessary to actuate the arm 76 whereby the shaft 75 will be rocked and the abutment 174 in the upper end of the lever 174 actuated to permit the pawl 65 to draw back into engagement with a succeeding tooth on the rack 63 so that upon the release of the arm 76, the spring 71 will return the arm 76 and the abutment 174 to actuate the pawl 65 to advance the rack 63 and therewith the platen P a letter space distance.

When an impression is made, the lever 174 is similarly actuated, it being connected by the link 77 with the crosspiece 78 resting in the slot 79 of the trip lever 34, the crosspiece 78 engaging the bottom of the slot 79 and being actuated forwardly with the trip lever 34 when the finger piece 28 is depressed to effect an impression.

The ribbon 42 is advanced from the supply reel 80 to the take-up reel 81, the supply reel 80 being preferably rotatably mounted at the upper end of a post extending up from a flange 2 projecting from the side wall 6 and the take-up reel 81 being preferably connected to rotate with a post 82 pivotally connected to a second flange 2 projecting from the side wall 7 and having fixed at its lower end a ratchet wheel 83 disposed above an arm 84 also fixed to said post 82. To a pin extending up from the plate 2, there is pivotally connected a holding pawl 85 maintained in engagement with the ratchet wheel 83 by the spring 86. On the arm 84 there is pivotally mounted an advancing pawl 87 maintained in engagement with the ratchet wheel 83 by the spring 88. The arm 84 is operatively connected by the link 89 with the downwardly extending projection 90 fixed to the shaft 75.

From the foregoing, it will thus appear that whenever the shaft 75 is rocked, a letter space of the platen P will be effected and the feed of ribbon 42 effected.

For letter spacing the platen P without effecting an impression, the space bar 11 may be depressed in the usual way, it being connected by the rearwardly extending bars 91 and 92 with the sleeve 93 rotatably mounted on the shaft 57, which sleeve 93 in turn is provided with a rearwardly extending arm 94, the rear end of which is adapted to engage the lower face of the arm 76, thereby to effect rocking of the shaft 75 and consequent actuation of the escapement.

The bracket 36 as will appear from Fig. 2 forming the right hand support for the shaft 35 is supported by the shaft 75 and sleeve 93, the shaft 75 and sleeve 93 being freely rotatable in the ends of said bracket 36.

For limiting the upward movement of the casting 48 when raising the platen P into position for receiving an impression from an upper case type 20, there is provided at the upper end of the rear wall 5 the stops 160 as aforesaid.

The mechanism associated with the type bars 15 is substantially the same as that associated with the type bars 16 except in the following respects mainly. The angular shaft 95, in place of the shaft 24 for the type bars 16, is journaled at its ends in the side walls 6 and 7 forwardly and downwardly relative to the shaft 24. The type bars 15 consequently are hooked shape, see particularly Fig. 2, to clear the type heads of the type bars 16. The trip lever 96, in place of the trip lever 34, is shorter than the trip lever 34 and is fixed to the hollow shaft 97, see particularly Fig. 3, one end of which shaft 97 is journaled on the diminished end of the shaft 35 and also journaled in the intermediate portion of the bracket 36 adjacent to the end of the shaft 35, while the other end of the shaft 97 is journaled in the side wall 7.

The crosspiece 78 also cooperates with this trip lever 97 extending through the slot 98, see Fig. 2, alining with the slot 79 of the trip lever 34 in position of rest. The hollow shaft 97 is provided with a forwardly extending projection 99, in place of the rearwardly extending projection 38, which projection 99 is in turn connected by the link 100 with the forwardly extending arm 101 fixed to the shaft 95. Here the selector finger 13 is formed at the end of a flexible arm 102 slidably mounted on the bar or lever 103, which arm 102 is provided with a finger engaging piece 104 similar to the finger engaging piece 28 associated with the selector finger 14.

The lever 103 is provided with a sleeve 113 slidably mounted on the shaft 95 but fixed to rock with the same. The shaft 95 is also provided with a rearwardly extending projection 105 connected by the spring 106 with the shaft 97.

The type bars 15 here too are not directly mounted on the angular shaft 95 but on a hollow sleeve 114 having an angular chamber corresponding to the angular conformation of the shaft 95 to permit sliding of the sleeve 114 along said shaft 95 but cause the sleeve 114 to rock with the shaft 95. The type bars 15 are also provided with plane faces 115 to be engaged by the resilient lips 116 of the resilient strip 117 extending from the sleeve 113 across the plane faces 115 of the type bars 15 to the sleeve 118 mounted at the other end of the sleeve 114 and fixed to the sleeve 114.

To define the normal position of the levers 27 and 103 when at rest, the cushioned stops 119 and 120 are provided to engage the projections 38 and 99 respectively, such stops 119 and 120 being preferably mounted on brackets extending from the side walls 6 and 7 respectively.

The platen P is preferably equipped with a standard paper feed shown in the present instance as having a rearwardly extending guide plate 107 and forwardly extending guide strips 108 with spring pressed rollers 109 for gripping the paper.

The embodiment illustrated in Figs. 7 and 8 distinguishes mainly from the first embodiment in that the keyboard here is divided into two parts, the portion 110 and the portion 111 which are adapted to be actuated for printing, in this respect laying greater emphasis on the separation between the left hand operated keys and the right hand operated keys so that the student will more

definitely have before him keys grouped for the left hand and the keys grouped for the right hand.

The keyboard section 110 is in the present instance provided with depressions 121 identical in number and position to the depressions 9 and 10 on the left hand side of the line 12 of the embodiment illustrated in Fig. 2 and the keyboard section 111 is provided with depressions 122 identical in number and position to the depressions 9 on the right hand side of the line 12 of the embodiment illustrated in Fig. 2.

The keyboard section 110 is provided with two rearwardly extending arms 123 and 124 and the keyboard section 111 is provided with two rearwardly extending arms 125 and 126.

The arms 123 and 124 are provided with sleeves 127 and 128 respectively which are rotatably mounted on the shaft portion 129 which is journaled at its left hand end in the side wall 130 of the frame 131 and at its right hand end in the bearing bracket 132 extending up from the base plate 133 of the frame 131.

The arms 125 and 126 on the other hand are provided with sleeves 134 and 135 respectively which are rotatably mounted on the shaft portion 136 which is journaled at its right hand end in the side wall 131 and at its left hand end in the bearing bracket 132. The sleeve 128 has formed thereon the trip arm 138, similar in shape to the trip arm 34 shown in Fig. 2, which trip arm is adapted to cooperate with the spurs of the type bars 139 similar to the type bars 16 and similarly mounted to the mounting of the type bars 16. The sleeve 134 on the other hand has formed thereon the trip arm 140, similar in shape to the trip arm 96 shown in Fig. 2, which trip arm 140 is adapted to cooperate with the spurs of the type bars 141 similar to the type bars 15 and similarly mounted to the mounting of the type bars 15.

With the present construction, the links 39 and 100 of the embodiment shown in Fig. 2 are omitted, since the trip arms are here directly actuated by the keyboard sections 110 and 111 respectively. With the present construction, the platen 142 may be shifted and the line spacing, letter spacing and ribbon feed effected in a manner similar to that shown in the embodiment of Fig. 2 and therefore such operative connections are not shown.

The keyboard sections 110 and 111 are each provided with an abutment plate 143 to cooperate with a spring 144 mounted on a pin 145 extending upwardly from the base plate 133 as shown in Fig. 7 to effect the return of the respective keyboard sections to positions of rest after depression.

The selector lever for the type bars 139 consists of a short curved portion 146 having slidably mounted thereon the straight arm 147 provided with a finger engaging knob 148 and a depression engaging lug 149 to cooperate with the depressions 121 of the keyboard section 110.

The selector lever for the type bars 141 consists on the other hand of a curved portion 150 having slidably mounted thereon a straight arm 151 with a finger engaging knob 152 at the front end thereof and a depression engaging lug 153 for engaging the depressions 122 of the keyboard section 111.

It is obvious that various changes and modifications may be made to the details of construction without departing from the general spirit of the invention as set forth in the appended claims.

I claim:

1. The combination with a type bar printing area, of a shaft below said printing area, a plurality of type bars rotatably and slidably mounted on said shaft, a selector slidably mounted but fixed to rock with said shaft, means connecting said selector to said type bars to slidably actuate said type bars relative to said printing area upon slidable actuation of said selector along said shaft, a plurality of character designating areas corresponding to said type bars and positioned to define the position of said selector according to the type bar to be selected, said selector having a finger to register with the character designating area corresponding to the type bar positioned by said selector and thus guide the operator in the selection of the type bar desired, said type bars having type adjacent their upper ends and spurs at their lower ends, and a trip operatively associated with said selector to engage the spur of the type bar selected and rock such type bar and thereby the type carrying end thereof into impression creating position on said printing area when said selector is depressed.

2. The combination with a platen having a type bar printing area, of a shaft below said printing area, a plurality of type bars rotatably and slidably mounted on said shaft longitudinally of said platen, a selector slidably mounted but fixed to rock with said shaft, means connecting said selector to said type bars to slidably actuate said type bars relative to said platen and position the type bar selected at said printing area upon slidable actuation of said selector along said shaft, a keyboard having a plurality of character designating areas corresponding to said type bars and positioned to define the position of said selector according to the type bar to be selected, said selector having a finger to register with the character designating area corresponding to the type bar positioned by said selector and thus guide the operator in the selection of the type bar desired, said type bars having type adjacent their upper ends and spurs at their lower ends, and a trip operatively associated with said selector to engage the spur of the type bar selected and rock such type bar and thereby the type carrying end thereof into impression creating position on said printing area when said selector is depressed.

3. The combination with a type bar printing area, of a shaft disposed below said printing area, a plurality of type bars rotatably and slidably mounted on said shaft, a selector slidably mounted but fixed to rock with said shaft, means connecting said selector to said type bars to slidably actuate said type bars along said shaft and position the type bar selected at said printing area upon actuation of said selector along said shaft, a keyboard having a plurality of character designating areas corresponding to said type bars and positioned to define the position of said selector according to the type bar to be selected, said selector having a finger to register with the character designating area corresponding to the type bar position by said selector, said type bars having type adjacent their upper ends and spurs at their lower ends, and means operatively associated with said selector to engage the spur of the type bar selected and rock such type bar and thereby the type carrying end thereof into impression creating position on said printing area when said selector is rocked with said shaft about its axis.

4. The combination with a type bar printing

- area, of two parallel shafts below said printing area, a group of type bars rotatably and slidably mounted on each shaft, two groups of character designating areas jointly corresponding to the 5 keys of a universal keyboard, one group of areas corresponding to the type bars on one shaft and to the keys adapted to be manipulated by the left hand of an operator and the other group of areas corresponding to the type bars on the 10 other shaft and to the keys adapted to be manipulated by the right hand of an operator, two selectors, one selector connected to one of said groups of type bars and slidably mounted on one of said shafts and the other selector connected 15 to the other of said groups of type bars and slidably mounted on the other of said shafts to slidably actuate said type bars along said shafts relative to said printing area and position the type bar selected at said printing area, each selector 20 having a finger to register with the character designating area corresponding to the type bar positioned by said selector and thus guide the operator in the selection of the type bar desired; one of said shafts being farther removed 25 from said printing area than the other, the type bars on the latter more distantly removed shaft being longer than the type bars on the shaft closer to said printing area and U-shaped to clear the shorter type bars when actuated into impression creating position, and means operatively 30 associated with each of said selectors to rock the type bar selected and thereby the type carrying end thereof into impression creating position on said printing area when said selector is rocked 35 with said shaft about its axis.
5. The combination with a common printing area, of a keyboard having a plurality of character designating areas corresponding to the keys of a universal keyboard and arranged in two 40 groups, one group for the left hand of an operator and the other for the right hand of an operator, and two typewriter actions, one action for each of said groups and each consisting of a shaft below said printing area, a group of type bars 45 rotatably and slidably mounted on said shaft, a selector arm connected to said group of type bars to slidably actuate said group of type bars relative to said printing area and position the type bar selected at said printing area, a selector finger 50 on said selector arm to register with the character designating area corresponding to the type bar positioned by said selector, one of said shafts being farther removed from said printing area than the other, the type bars on the latter more 55 distantly removed shaft being longer than the type bars on the shaft closer to said printing area and U-shaped to clear the shorter type bars when actuated into impression creating position, and means operatively associated with said selector 60 to rock the type bar selected and thereby the type carrying end thereof into impression creating position on said printing area when said selector is rocked with said shaft about its axis.
6. In a typewriter, the combination with a 65 keyboard having a plurality of character designating areas corresponding to the keys of a universal keyboard and divided into two sections, of two shafts, a plurality of type bars having type at their upper ends said type bars corresponding 70 to the character designating areas of said keyboard and divided into two groups, one group rotatably and slidably mounted on one of said shafts and operatively associated with one section of said keyboard, the other group rotatably 75 and slidably mounted on the other of said shafts
- and operatively associated with the other section of said keyboard, two selectors, one selector fixed to rock one of said shafts and operatively associated to slide with one group and register with any of the character designating areas in one section of the keyboard to position for printing the type bar corresponding to the character designating area in registration with such selector; the other selector fixed to rock with the other shaft and operatively associated to slide with the other group and register with any of the character designating areas in the other section of the keyboard to thereby position for printing the type bar corresponding to the character designating area in registration with such selector, means for pivotally mounting said keyboard sections, and means for operatively associating the type bar selected with its associated keyboard section so that the actuation of either of said 10 selectors into engagement with a keyboard section and the resulting actuation of the keyboard section so engaged will rock the type bar selected and thereby the type carrying end thereof to effect a printing impression.
7. In a typewriter, the combination with a 15 keyboard having a plurality of character designating areas corresponding to the keys of a universal keyboard and staggered relative to one another to be spaced from one another on an imaginary projected line, of two shafts, a plurality of type bars rotatably and slidably mounted on each shaft and having type at their upper ends, said type bars corresponding to said character designating areas and divided into two 20 groups, two selecting levers, one lever fixed to one of said shafts and operatively associated to slide with one group of said type bars relative to said imaginary projected line and register with the character designating area corresponding to the type bar selected, the other lever operatively associated to slide with the other group of said type bars relative to said imaginary projected line and register with the character designating area corresponding to the type bar thereby selected, and two trip devices, one operatively 25 associated with one selecting lever and the other operatively associated with the other selecting lever to rock the type bars selected and thereby the type carrying ends thereof to effect a printing impression upon the actuation of a selecting 30 lever.
8. In a typewriter, the combination with a 35 keyboard having a plurality of character designating areas corresponding to the keys of a universal keyboard and offset relative to one another to be spaced from one another on an imaginary projected line, of two shafts, a plurality of type bars rotatably and slidably mounted on each shaft and having type at their upper 40 ends, the group of type bars mounted on one shaft corresponding to the character designating areas ordinarily operated by the left hand of an operator and the other group of type bars mounted on the other shaft corresponding to the character designating areas ordinarily operated by the right hand of an operator, two selecting levers, each lever fixed to one of said shafts and operatively associated to slide with one of said 45 groups of type bars relative to said imaginary line to select the type bar desired, a finger on each of said levers to register with the character designating area corresponding to the type bar selected to thereby permit the operator to select the type bar by registering said finger with the character designating area corresponding to the type 50

bar desired, and trips operatively associated with said selecting levers to rock the type bar selected and thereby the type carrying end thereof to effect a printing impression upon the rocking 5 actuation of said selecting levers.

9. In a typewriter, the combination with a keyboard having a plurality of character designating areas corresponding to the keys of a universal keyboard and offset relative to one another to be spaced from one another on an imaginary projected line, of two shafts, a group of type bars having upper and lower case type at their upper ends and slidably pivotally mounted on one of said shafts and corresponding to the character designating areas ordinarily operated 10 by the left hand of an operator and another group of type bars having upper and lower case type at their upper ends and slidably pivotally mounted on the other of said shafts and corresponding to the character designating areas ordinarily operated 15 by the right hand of an operator, two pivotally mounted selecting levers, each fixed to one of said shafts and operatively associated to slide with the group of type bars on such shaft relative to said imaginary line to 20 select the type bar desired in said group to the exclusion of the other group, a finger on each of said levers to register with the character designating area corresponding to the type bar selected to thereby permit the operator to select 25 the type bar by registering said finger with the character designating area corresponding to the type bar desired, a trip operatively associated with each of said selecting levers to rock the type bar selected about its shaft to effect a printing 30 impression upon the actuation of such selecting lever, a record supporting platen positioned above said shafts to cooperate with the type carrying ends of said type bars, and means for shifting said platen into position to receive an impression from the upper case type of said type bars.

10. In a typewriter, the combination with a keyboard having a plurality of character designating areas corresponding to the keys of a universal keyboard and offset relative to one another to be spaced from one another on an imaginary projected line, of two shafts, a group of type bars having upper and lower case type at their upper ends and slidably pivotally mounted on one of said shafts and corresponding to the character designating areas ordinarily operated 10 by the left hand of an operator and another group of type bars having upper and lower case type at their upper ends and slidably pivotally mounted on the other of said shafts and corresponding to the character designating areas ordinarily operated 15 by the right hand of an operator, two pivotally mounted selecting levers, each fixed to one of said shafts and operatively associated to slide with the group of type bars on such shaft relative to said imaginary line to 20 select the type bar desired in said group to the exclusion of the other group, a finger on each of said levers to register with the character designating area corresponding to the type bar selected to thereby permit the operator to select 25 the type bar by registering said finger with the character designating area corresponding to the type bar desired, a trip operatively associated with each of said selecting levers to rock the type bar selected about its shaft to effect a printing 30 impression upon the actuation of such selecting lever, a record supporting platen positioned above said shafts to cooperate with the type carrying ends of said type bars, and means for shifting said platen into position to receive an impression from the upper case type of said type bars.

HARRY BATES.
